UNITED STATES PATENT OFFICE.

WALTER H. HARTMAN, OF JORDAN, MINNESOTA.

JAR-LID SEALER.

Application filed April 16, 1924. Serial No. 706,914.

To all whom it may concern:

Be it known that I, WALTER H. HARTMAN, a citizen of the United States, residing at Jordan, in the county of Scott and State 5 of Minnesota, have invented certain new and useful Improvements in Jar-Lid Sealers, of which the following is a specification.

This invention relates generally to jars, 10 and has more particular reference to a means for rigidly sealing the lid of the jar in place, for preventing the access of air into the jar, and the consequent spoiling of its contents.

15 The primary object of the present invention resides in the provision of a sealing means, that constitutes the provision of a pair of bails pivotally secured to a member encircling the neck of a jar, and adapted 20 to be extended over the jar lid and joined together in a tight manner through the medium of certain elements constituting essentials of the present invention for adequately securing the lid upon the jar.

25 An additional object is to provide a sealing means for jar lids, that may be manufactured and marketed at extremely small cost, and one that may be operated in a simple manner.

30 With the foregoing and other objects in view, as the nature of the invention will be better understood, the same comprises the novel form, combination, and arrangement of parts hereinafter more fully described, shown in the accompanying drawing, and claimed.

35 In the drawing, wherein like reference characters indicate corresponding parts throughout the several views:

40 Figure 1 is a fragmentary side elevational view of a jar, the lid thereof being secured in place, through the medium of a fastening means constructed in accordance with the present invention.

45 Figure 2 is a top plan view thereof.

Figure 3 is a side elevational view of one of the units that constitutes an essential part of the present invention, and

50 Figure 4 is a fragmentary elevational view of the twisted wire member that is adapted to be secured around the neck of the jar, said twisted wire member constituting the provision of a pair of wires intertwisted, and the ends thereof being joined together, in a manner preferably as shown in this figure.

Now having particular reference to the drawing, 5 indicates the jar, the upper open end of which is enlarged, at 6, for providing a shoulder 7, and upon which upper 60 open end is adapted to be disposed a lid 8, while intermediate said lid and the jar is adapted to be inserted a rubber packing ring 9, which is a feature now well known.

In carrying out the present invention, 65 it is necessary that the outer surface of the jar lid 8 be formed centrally with a raised knob or head 10, that is formed with a transverse channel 11.

My lid fastening means per se, constitutes 70 the provision of a member 12, adapted to be extended around the neck of the jar 5, beneath the shoulder 7 formed by the enlargement 6, at the upper end of the jar.

This member 12 constitutes the provision 75 of a pair of wire links, that are intertwined as shown, the ends thereof being joined together by intertwisting, designated 13 and 14 respectively in Figure 4.

Secured to the twisted wire member 12 80 encircling the jar neck, and at diametrically opposite points thereon, are the free ends of the legs of wire bails 15 and 16, that are adapted to be extended inwardly over the jar head 8, in a manner as clearly shown 85

in Figures 1 and 2. Adapted to be inserted in the cross panel 11 of the lid carrying head or knob 10, is a bolt 17, that is formed with spaced oppositely extending screw threads 18 and 19. Arranged upon the oppositely extending screw threads of this bolt are nuts 20 and 21, the lower edge of the nut 20 being formed with an inwardly extending hook 22, under which the closed end of the bail 16 is adapted to be arranged as shown in the top plan view, Figure 2. The other nut 21 is formed upon its lower end with a longitudinally extending opening 23, through which is to be passed the closed end of the other bail 15. 100

One end of the bolt 17 is squared as at 24, whereby the same may be turned through the medium of a key, and it will at once be apparent that after the lid 8 has been placed upon the jar, and the bail 15 extended thereover, and the bolt placed within the channel of the head or knob, the other bail 16 may be arranged within the hook 22 of the nut 20, after which a turning of the bolt in one direction will occasion the inward movement of the nuts 20 and 21, for manifestly drawing the bail 110

tightly together upon the lid for rigidly securing the same in position upon the jar.

It will thus be seen that I have provided a highly novel and simplified form of jar lid fastener, and one that will meet with all of the requirements for a successful commercial use.

Minor changes may be made in the invention, without departing from the spirit and scope of the appended claim.

Having thus described my invention, what I claim as new and desire to secure by Letters Patent is:

In a jar lid fastener of the character de-

scribed, a member surrounding the neck of the jar, a pair of bails pivotally secured to the member at opposite points thereon, a bolt adapted to be arranged upon the jar lid and formed with oppositely extended threads at its ends, a nut engaged with one thread of the bolt and having an opening through which extends one bail, and a second nut having a hooked extension for engaging the other bail and adapted to be received on the other thread of the bolt.

In testimony whereof I affix my signature.

WALTER H. HARTMAN.
